OF JERSEY CITY, NEW JERSEY, A CORPORATION OF NEW JERSEY

CONDENSATE REHEATER

Application filed November 20, 1926. Serial No. 149,651.

This invention relates to condensers and with respect to its more specific features to condensate reheaters.

One type of condensate reheater to which this invention relates more particularly is that in which exhaust steam is supplied to contact directly with the condensate. Usually exhaust steam is bled from a point of relatively high absolute pressure and the air and uncondensable gases in the reheater is vented back to the condenser at a point of substantially a maximum degree of vacuum in the condenser. This results in a loss of efficiency since the high degree of vacuum at the vent results in a path of less resistance for the steam in the conduit bleeding steam from the condenser to the reheater than in the main path through the condenser between corresponding points.

An object of this invention is to produce substantially the same resistance to the flow of the steam supplied to the reheater and thence to the vacuum pump as exists through the condenser proper. This is obtained in the preferred form of the invention by venting the condensate reheater to a point in the condenser at a region of lower absolute pressure than exists at the steam entrance but not the lowest pressure within the condenser.

The reason for producing the same resistance through the reheater to the point of discharge into the condenser as occurs through the condenser to the point at which air and uncondensable gases are returned to the condenser from the reheater is as follows: Efficient operation of the condenser depends largely upon the smooth flow of steam over the tubes. When the condenser is of proper design the smooth flow of steam to the points of discharge of condensate and uncondensable gases eliminates dead spots or air pockets that would otherwise be caused by turbulence. It is at once evident that a return of air and uncondensable gases from the reheater at a pressure higher than that which exists in the condenser at the point of return will cause a blast of air to enter the condenser at that point thus breaking the stream lines in the main body of steam flowing through the condenser. This is one of the chief causes of

the formation of undesirable dead spots and air pockets.

Since the velocity of the fluid passing through the reheater is not increased at any point in its circuit, it follows that the residual fluid returned to the condenser at a point in the condenser having substantially the same pressure as the pressure in the return pipe will enter the condenser with a velocity substantially that existing in the main body of steam.

The invention will be more clearly understood by reference to the accompanying drawings forming part of the specification and in which is shown diagrammatically a condenser, parts being shown in cross section to illustrate the operation more clearly.

Referring to the drawing, the invention is shown applied to a condenser having a shell A and an inlet pipe B for admitting the steam to be condensed. The condenser is of the type commonly known as a surface condenser in which there is provided a plurality of tubes C arranged transverse to the direction of steam flow within the casing A toward the condensate outlet D. The shell A is shown mounted on a concrete base E and its steam inlet pipe B is adapted to be connected in any suitable manner with a turbine supported by the floor slab F.

The condensate withdrawn from the outlet D is, of course, merely pure water and usually it is desirable to re-use this for boiler feed. Prior to its injection into the boiler the condensate is, in the most approved practice, reheated by steam drawn from a suitable point in the system. It is preferable that this steam shall have converted a part of its heat into mechanical energy, although a large part of the heat remains latent in the steam and it is convenient to utilize this latent heat for raising the temperature of the condensate.

A convenient arrangement for reheating the condensate is shown in the drawing and includes a chamber G connected by means of a pipe H to the condensate outlet D from the casing A and provided with a weir J connecting as a trap to prevent the return of gases or steam through the pipe H. For this pur-

pose the rim of the weir J is elevated at least to the level of the entrance orifice K connected to the pipe H so that the water lever submerges the orifice at all times.

The reheating steam is admitted to the chamber G below the weir J so that any gas or uncondensable vapor must pass through the sheet of water passing over the weir J in order to leave the chamber G. The reheating steam for chamber G is supplied through a pipe L at an orifice O situated below the weir J, the pipe L being connected with a suitable orifice P formed integrally with the inlet pipe B. Preferably the steam inlet P is formed with an upwardly directed mouth, as shown at Q, so that a current of steam is directed into the pipe L.

In order to create a flow of steam through the pipe L and into the chamber G, it is desirable that a suitable vacuum should be formed within said chamber and maintained for, if this is not done, air and uncondensable gases will collect in the chamber G and cause a back pressure sufficient to stop the flow of steam. To this end there is provided an air outlet pipe R leading from the upper part of the chamber G back to the interior of the condenser shell A. The vacuum produced by suitable evacuating means (not shown) is sufficient to withdraw the uncondensable air and vapor from the chamber G thereby maintaining the desired vacuum therein.

Hitherto it has been the practice to connect the air removal pipe or vent R at the region from which air and uncondensable gas is withdrawn from the condenser shell A, as for instance is indicated by S. It has been found that this practice tends to create a partial short circuit around the tubes C so that far too great a proportion of steam passes through the pipe L and more than can be utilized in reheating the condensate in the chamber G. By this invention it is proposed to produce a path for the steam through the chamber G and thence to the air evacuating means having a pressure drop commensurate with the corresponding drop between the steam inlet pipe and the region S for air withdrawal. To this end the air withdrawal pipe R from the reheater chamber G is connected with the shell A at a region of pressure higher than that existing at S or the lower outlet of the main condenser shell A. The air withdrawal pipe R is therefore connected to the casing A at an opening T relatively remote from the region S whereby the gases entering the opening T are caused to pass around some of the tubes C in order to reach and enter the orifice b. In this instance the opening T is located at the side of the shell and a guard U is provided to prevent condensate from flowing into this opening, and to cause the returning uncondensable gases to enter the condenser at such an angle that

the stream lines of the main body of steam will not be disturbed thereby.

The removal of the air and uncondensable gases at the orifice b may be accomplished in any suitable manner. In this embodiment there is indicated a cooler and devaporizer V for such a mixture. At this point it should be noted that the residual gas entering the condenser from the reheater must pass over some of the coldest tubes in the condenser before entering the cooler V. This feature materially reduces the load on the cooler as well as that on the cooler exhaust pump (not shown).

Another advantage obtained by passing the residual gases over the cold tubes outside of the cooler is this; if unusual conditions prevail whereby an unnecessarily large amount of steam is drawn into the reheater G, the excess of steam will be condensed by the cold tubes and not drawn into the cooler. The reheated condensate from the chamber G is withdrawn through an opening W near the bottom of the chamber and a pipe X connected therewith by means of a suitable pump Y and delivered through a discharge pipe Z to a suitable point for feeding into the boiler (not shown).

Thus by the above construction are accomplished, among others, the objects hereinbefore referred to.

I claim:

1. The combination of a condenser having an outlet for condensate, a reheater for said condensate, a pipe leading from the reheater to return air and uncondensable gases collected therein back to the condenser, and means on the condenser adjacent said pipe to direct the returned air and uncondensable gases across the condenser in a path substantially normal to the flow of condensate towards the outlet and to prevent said condensate from entering the return pipe.

2. The combination of a condenser having an outlet for condensate formed by the cooling means of said condenser, a reheater for said condensate, a pipe leading from the reheater to return air and uncondensable gases collected therein back to the condenser at a point above the outlet, means to withdraw the returned air and uncondensable gases from the condenser, said means being located at a point relatively remote from the point of connection of the return pipe, and a baffle on the condenser adjacent said pipe to direct the returned air and uncondensable gases across the condenser cooling means to the air withdrawal means in a path substantially normal to the flow of condensate towards the outlet and to prevent said condensate from entering the return pipe.

In testimony whereof I have signed this specification.

PAUL A. BANCEL.
